UNITED STATES PATENT OFFICE.

KERTY W. HESTER, OF MUNFORDVILLE, KENTUCKY.

COMBINED COTTON-HOLDER AND MASSAGE DEVICE.

1,158,214.

Specification of Letters Patent.

Patented Oct. 26, 1915.

Application filed June 12, 1915. Serial No. 33,686.

To all whom it may concern:

Be it known that I, KERTY W. HESTER, a citizen of the United States, residing in Munfordville, in the county of Hart and 5 State of Kentucky, have invented a new and useful Combined Cotton-Holder and Massage Device, of which the following is a specification.

The object of this invention is to provide a simple and efficient device which may be applied to the finger of the operator for holding a small quantity of absorbent cotton or similar absorbent material to be used in absorbing pus and similar exudations 15 from diseased gums and to combine therewith a device which may be used to massage the gums and thus stimulate circulation after the pus has been removed.

According to this invention I employ a 20 thimble or finger cot which is preferably made of rubber adapted to fit over a small quantity of absorbent cotton placed on the end of the finger in such manner as to securely hold the cotton in place. This device 25 is formed with a tab by means of which it may be readily withdrawn from the finger when desired. In connection with the cotton holder I use a massage device which consists of a segment of rubber provided with 30 teeth or a roughened surface and which is joined to the cotton holder. The massage device is formed with means for holding it in place on the finger when adjusted for use.

In the accompanying drawings, Figure 1 35 is a perspective view of the combined cotton holder and massage device. Fig. 2 shows a transverse section on the line 2—2 of Fig. 1. Fig. 3 is an elevation showing the inner side of the massage device. Fig. 4 is an elevation 40 showing the toothed or roughened surface of the massage device. Fig. 5 is a longitudinal section on the line 5—5 of Fig. 4. Fig. 6 is a side elevation showing the device in condition for use as a cotton holder. Fig. 7 45 shows a longitudinal section of the device in condition for use for massage purposes.

The combined cotton holder and massage device is preferably made of rubber and may be formed from one piece of material. 50 It comprises two parts, a cotton holder *a* and a massage device *b*. The cotton holder is in the form of a hollow frustum, its inner or larger end being reinforced by an annular bead *a'* and its outer end carrying a tab *a''* by means of which it may be withdrawn from the finger when desired. The massage

device is tapered outwardly from the bead *a'* and is semi-circular in cross section, one side being open, as shown, while the end *b'* is closed. The two edges *b''* of the part *b* are 60 connected by a strap *c* which is joined to the edge of the front wall *b'* by a longitudinal strap *c'*. These straps are located at the outer or smaller end of the device.

a'' indicates a tab to be used for manipulating and adjusting the straps.

The outer surface of the part *b* is provided with teeth *d* which are preferably formed of the same material as the body of the device, but the device may be formed 70 with other kinds of teeth, or may be roughened in any suitable way.

When the device is used to hold absorbent cotton the latter is placed over the finger in the manner indicated in Fig. 6, and then 75 the device is drawn over the cotton and over the end of the finger as shown. When thus adjusted the cotton may be pressed on the gum in such manner as to squeeze out and absorb the pus. Preferably the thumb and 80 index finger of the hand are employed with similar holders when treating the gum to remove pus therefrom. After the gum has been thus treated the holder or holders may be withdrawn by means of the tab *a''* and the 85 cotton may then be burned or otherwise destroyed.

When the device is used for holding cotton the straps *c*, *c'* are turned over onto the outside of the part *b*, as shown in Fig. 6, so 90 that the finger of the user may be easily inserted. When the device is used for massage purposes, the straps *c*, *c'* are turned to the inner side of the part *b* and the part *a* is reversed and inserted into the part *b* so 95 that the finger of the user may be inserted into the massage device in the manner indicated by dotted lines in Fig. 7. When thus applied to the finger the device may be rubbed over the gums in order to stimulate 100 circulation.

The device thus constructed is very simple in construction, may be made at a low cost, can be used with facility and is very efficient. It may be employed not only for treating 105 the gums and removing pus therefrom, but may be also used to clean the teeth, tongue and other parts of the mouth.

I claim as my invention:

1. A holder for absorbent cotton, comprising 110 a hollow frustum shaped finger cot open clear through, having an annular reinforce-

ing bead at its inner or larger end and an outwardly projecting tab at its outer end.

2. A holder for absorbent cotton, comprising a hollow frustum shaped finger cot or thimble open at opposite ends and provided with a massage portion projecting from its inner end.

3. A holder for absorbent cotton, comprising a hollow frustum shaped finger cot or thimble open at opposite ends and provided with a massage portion projecting from its inner end which is provided with a roughened or toothed surface on its outer side, has an open inner side, and is provided 15 with straps connecting its opposite side edges.

4. A holder for absorbent cotton, comprising a hollow frustum shaped finger cot or thimble open at opposite ends and which is provided with a massage device projecting from its inner end which is semi-circular in cross-section, tapers from its inner end outwardly, and is provided with flexible straps connecting its opposite side edges near its outer end with a longitudinal strap 25 connected to the outer end of the device.

In testimony whereof, I have hereunto subscribed my name.

KERTY W. HESTER.
